UNITED STATES PATENT OFFICE.

WILLIAM H. HANEY, OF CINCINNATI, OHIO, ASSIGNOR TO HENRY KORF, JR., OF SAME PLACE.

CANDLE-MOLD GAGE.

SPECIFICATION forming part of Letters Patent No. 269,664, dated December 26, 1882.

Application filed September 11, 1882. (No model.)

To all whom it may concern:

Be it known that I, WILLIAM H. HANEY, a citizen of the United States, residing at Cincinnati, in the county of Hamilton and State of Ohio, have invented certain new and useful Improvements in Candle-Mold Gages, of which the following is a specification.

My invention consists in applying a pair of peculiarly-constructed gages to the frame of a candle-molding machine for the purpose of limiting the descent of the follower that carries the gang of pistons, in order that said pistons may be adjusted within their respective molds to produce candles of various lengths, these gages being supplementary to the ordinary racks, pinions, and pawls wherewith such followers are usually operated, and being designed to afford a much more accurate range of adjustment than could possibly be effected with the racks and pinions alone, as hereinafter more fully described, and pointed out in the claims.

In the annexed drawings, Figure 1 is an end elevation of a portion of a candle-molding machine with one of my gages attached thereto. Fig. 2 is an enlarged elevation of the gage, seen from the inside of the machine. Fig. 3 is a vertical section of the gage, taken in the plane of its slot, the follower being shown supported on the extended nut of said gage. Fig. 4 is a sectionized elevation of one of the molds and its accessories. Fig. 5 is a modification of the invention.

A represents a portion of the end frame of a candle-molding machine, said frame having journaled in it two intermeshing pinions, B B', that gear with vertical racks C C', the lower ends of the latter being adapted to support a follower, D. This follower has secured to it a gang of tubular pistons, E, through which the wicks pass, each piston being provided with a conical head, F, that traverses the cylindrical molds G, as seen in Fig. 4.

As above described, the machine is essentially the same as those in general use.

Attached preferably to the brace H of the frame, by a bolt, I, or otherwise, is the gage J, the lower part of which takes the shape of a flat plate, slotted longitudinally at K to admit said bolt. Furthermore, the lower part of plate J has a flange or foot, L, to rest on the

floor, while the upper portion of said plate is screw-threaded at N to receive an extended nut, O, and a jam-nut, P.

Ribs R R' may be cast on the inner face of brace H for the purpose of maintaining the gage in an erect position.

The plate J is secured to brace H in the manner described, the slot K being provided to compensate for differences in the height of said brace or for irregularities in the floor, while the foot L enables said plate to sustain the necessary weight. The gages having been thus secured in position, one at each end of the machine, and it being desired to mold very short candles, the extended nut O is run up to the top of screw N and locked there by the jam-nut P, the follower D having been previously elevated as far as the racks C C' will permit. This follower is then allowed to descend and rest on nut O, and as all the pistons E are attached to said follower it is evident the position of heads F within their respective molds G will be determined by the location of said nut; but if it should be desired to make very long candles the nut O is run down to the bottom of screw N, thereby allowing the pistons E and their heads F to descend to the lower end of molds G. From this description it is evident that candles of any size may be produced within the limits afforded by the molds G and screw N.

In the modification of my invention seen in Fig. 5 substantially the same results are obtained by a bracket, S, having ratchet-teeth s, that engage with similar teeth, j, of the gage, said bracket having a laterally-projecting bolt, I', traversing the slot K, which in this case should extend almost the entire length of the gage; but as this ratchet-gage does not afford as many different degrees of adjustment as the screw N its use is not advised. Finally, the pawl T is to be used only for supporting the follower D while the adjustment of the gages is being effected. Hence it is apparent that my gages are to be used as supplementary devices to permit a more accurate range of adjustment of the follower D than could be afforded by the simple use of the customary racks, pinions, and pawls.

I claim as my invention—

1. In combination with a candle-molding ma-

chine of the class specified, a pair of vertically-adjustable supplementary gages or stops for limiting the descent of the follower that carries the pistons, which gages are to operate independently of the racks, pinions, and pawls wherewith said follower is raised and lowered, substantially as described.

2. A candle-mold gage consisting of the slotted plate J K, screw N, and extended nut or stop O, which latter is adapted to support the follower D, that carries the pistons E F of the molds G, in the manner described.

3. The combination of candle-mold frame H, slotted gage J K N, extended nut O, bolt I, and ribs R R', as and for the purpose specified. 15

In testimony whereof I affix my signature in presence of two witnesses.

WILLIAM H. HANEY.
